UNITED STATES PATENT OFFICE.

AIMÉ LOUIS VUILLIER, OF BROOKLYN, NEW YORK.

TONGS FOR IMMERSING TINNERS' ARTICLES.

SPECIFICATION forming part of Letters Patent No. 548,767, dated October 29, 1895.

Application filed July 27, 1895. Serial No. 557,371. (No model.)

To all whom it may concern:

Be it known that I, AIMÉ LOUIS VUILLIER, a citizen of the United States, residing at Brooklyn, in the county of Kings and State of New York, have invented a new and useful Tongs for Immersing Tinners' Articles, of which the following is a specification.

This invention relates to an improvement in the construction of tongs, such as are ordinarily used for tinning or retinning articles manufactured from sheet metal for giving to said articles a bright and new appearance and providing the same with a smooth and even coating and removing inequalities in the surface thereof.

The object of the present invention is to provide a novel form of tongs which shall be simple in construction, easy of manipulation, and not liable to get out of order, which shall be capable of holding and immersing a number of similar articles at one time and yet be easily controlled by a single operator, thus effecting a great saving in the number of workmen required, fuel consumed, and a consequent reduction of expense in the process and operation of tinning or retinning.

It is usual in tinning or retinning articles to immerse them first in a bath of molten tin, after which they are transferred to the grease-pot and immersed for a short length of time in a bath of hot grease. The effect of such immersion is to partially remelt the coating on the surface of the article and to spread the same evenly and uniformly, removing any surplus tin that may adhere to certain portions of the article and producing a smooth and even surface. It is important that the period during which the articles remain in the grease bath should be correctly timed. If left in the bath too long, too much tin will be removed therefrom, and if not immersed sufficiently long the coating will not be uniform and smooth or even. It is therefore necessary to be able to handle the articles quickly and with ease and it has been with this point in view that I have constructed the present form of tongs, which I shall now proceed to describe.

My invention consists in the novel combinations, details of construction, and arrangement of parts, as hereinafter fully set forth, and pointed out in the claims.

In the accompanying drawings, Figure 1 is a front view of my improved tongs, illustrating the manner in which a number of articles are immersed thereby in the grease-pot. Fig. 2 is a side elevation of my improved tongs complete with the clamping-arms closed. Fig. 3 is a similar view taken from the opposite side with the clamping-arms open. Fig. 4 is a plan view of the same. Fig. 5 is an enlarged perspective view of the adjustable bearing-collar for the rock-shaft and the pivoted clamp-arm. Fig. 6 is a detached view of the rock-shaft and its eccentric and operating crank arm or lever; Fig. 7, a similar view of the link interposed between the eccentric and the pivoted clamping-arm; Fig. 8, an end view of the pivoted supporting-hook and its swiveled block or yoke. Fig. 9 is a plan view of a portion of the temporary holding-frame. Fig. 10 is a side elevation of the same.

Similar numerals of reference indicate corresponding parts in the figures of the drawings.

1 represents the main supporting rod or bar of my improved tongs, provided with a longitudinal groove 2 for the purpose of keying the several collars and bearings hereinafter described to said supporting-rod for preventing them from turning thereon. At a suitable point intermediate the ends of the rod 1 the main supporting-hook 3 is swiveled thereto in the following manner: A swiveling-block 4 is provided with a central aperture or perforation 5, which receives the main supporting-rod 1, and is also provided with laterally-projecting oppositely-arranged studs 6, adapted to receive the lower ends of two metallic straps or arms 7, secured at their upper opposite ends upon opposite sides of the flat shank 8 of the main supporting-hook 3 and bolted thereto by means of the through-bolts 9, passing through both arms 7 and the shank 8 of said hook, being secured by nuts 10, as shown. The block 4 is held in place and at the desired point on the rod 1 by means of two collars 11, one upon either side of the block 4, said collars 11 surrounding the rod 1 and being secured thereto by means of setscrews 12.

13 indicates a traveling pulley running on an overhead track 14 and mounted in a suitable hanger 15, having at its lower end a loop

16 for engaging the main supporting-hook 3 and suspending the tongs, said loop or link 16 being pivotally connected with or swiveled to the pulley frame or hanger 15. The overhead track extends over the grease-pot and may also extend over the tinning bath, whereby by the tongs and the articles carried thereby may be conveyed from one bath to the other in the usual manner.

10 At or near the lower end of the main supporting-rod 1 is located one of the clamping-arms 17 of the tongs, which is made from a piece of bar-iron, preferably rectangular in cross-section and provided at one end with a collar 18, which surrounds the main supporting-rod 1 and is keyed thereto for preventing its rotation thereon. The collar 18 is further held in place by means of a set-screw 19, by means of which the position of the clamping-arm 17 may be adjusted lengthwise or longitudinally of the main supporting-rod 1 for the purpose which will appear.

20 and 21 indicate two of my clamping-bars, made from wrought or cast iron and provided with a series of V-shaped sockets or jaws 22 for engaging the articles to be tinned or retinned, there being ordinarily about twelve of such V-shaped jaws or sockets, though the number may be increased or diminished at the option of the manufacturer. The bars 20 and 21 are each provided with a central extension 23, which has a central aperture corresponding in shape and adapted to receive the clamping-arm 17. The clamping-bars 20 and 21 are thus adjustable lengthwise of the clamping-arm 17 and may be held at any required point by means of set-screws 24.

25 indicates a collar or bearing which is adjustable lengthwise of the main supporting-rod 1, to which it is keyed, and is held at any desired point by means of set-screws 26.

27 is a short clamping-arm projecting downwardly from said collar or bearing 25, similar in cross-section to the arm 17, and also provided with an adjustable clamping-bar 28, having a set-screw 29 for holding the same in place.

30 indicates a pivoted clamping-arm mounted upon a bolt 31, passing through it and through the bearing or collar 25 and held in place by means of a nut 32. A clamping-bar 33, similar to the bars 20, 21, and 28, is mounted on the arm 30 and adjusted by means of a set-screw 34, the arm 30 being bent, as indicated at 35, to bring the bar 33 into line with the other similar bars of the series.

36 indicates a rock-shaft which is journaled in a bearing formed in an extension 37 of the collar 25 and secured in place by means of a nut 38. Upon one end of the rock-shaft 36 is provided an eccentric 39, and beyond the outside of said eccentric is a crank or lever 40 for operating the same. A link 41 surrounds said eccentric at one end and at its other end connects with the inner end of the pivoted clamp-arm 30. Said link 41 is provided with a stop or short stud 42, which is adapted to

engage other stops 43 and 44, projecting radially from a hub or disk 45, which is formed at the inner end of the crank-arm or lever 40, the purpose of which is to limit the revolution of the rock-shaft 36, and thereby to limit, also, the throw of the clamping-arm 30.

The operation of the device is as follows: By turning the crank-arm or lever 40 in one direction the pivoted clamping-arm 30 is thrown outwardly, carrying the clamping-bar 33 away from its opposing bar 21. When in this position, the sheet-metal articles 46 to be tinned or retinned may readily be inserted and brought into engagement with the V-shaped socket or jaw 22 in the bars 20, 21, and 28. When the articles are all in such position, the crank-arm 40 is reversed, thereby throwing the clamping-arm 30 and its bar 33, also, into engagement with the articles mentioned, thereby firmly clamping said articles in place and preventing their escape while in the bath, it being impossible for the clamping-bar 33 to be accidentally withdrawn by reason of the action of the rock-shaft and its eccentric above described.

47 indicates a sliding weight, which is adjustable lengthwise of the main supporting-rod 1 and is adapted to be held at any desired point by means of a set-screw 48. 49 indicates a handle attached to the end of the main supporting-rod 1, by which the operator is enabled to control the position of the tongs.

By reason of the tongs being supported at a point intermediate the length of the main supporting-bar 1 by the hook 3 and providing such supporting-bar with the adjustable weight 47 the rod 1 may be nicely balanced and the extra weight of the articles to be tinned or retinned counterbalanced by shifting the adjustable weight 47. Thus the operator by grasping the handle 49 may readily and easily tilt the tongs for immersing the articles in the grease-pot or lifting them therefrom in a manner which will be readily understood. An eye or hook 50, clamping-collar 51, and set-screw 52 provide for the attachment of a suitable supporting-chain for holding the tongs elevated, when desired.

In Figs. 9 and 10 I have shown a temporary rack or cage, which is composed of three or more pieces of wood 53 in parallel relation to each other, connected at several points by threaded bolts or rods 54, as indicated. The positions of the outer pieces 53 may be adjusted nearer to or farther from the central piece 53 by means of suitable nuts 55. The pieces 53 are each provided with a corresponding series of notches or depressions, which are located at a distance apart corresponding to the distance between the sockets or jaws 22 in the clamping-bars 20, 21, 28, and 33 of the tongs. The object of making the pieces 53 adjustable toward and away from each other is to provide for different sizes of sheet-metal articles placed therein, and the object of the device as a whole is to enable such articles to be placed in the same rela-

tive position which they will occupy when clamped by the tongs. The articles are temporarily placed in the notches in the pieces 53, and when it is desired to fill the tongs the 5 clamping-bars are placed over the articles 46 until the jaws 22 engage said articles, when by operating the crank arm or lever 40 said articles are firmly clamped between the tongs and are now ready to be immersed, as above 10 explained.

Various changes in the form, proportion, and the minor details of construction may be resorted to without departing from the principle or sacrificing any of the advantages of 15 this invention.

Having thus described my invention, what I claim is—

1. The combination with the main supporting rod, of several clamping arms adjustable thereon, and provided with the slideable and adjustable clamping bars, arranged to operate in the manner specified.

2. The main supporting rod, in combination with a pair of clamping arms adjustable thereon, a pivoted clamping arm also adjustable thereon, and means for operating said pivoted arm, for the purpose substantially as described.

3. The main supporting rod, in combination with a pair of clamping arms, having a slideable adjustment thereon, a pivoted clamping arm also adjustable lengthwise upon said supporting rod, and a lever for operating said pivoted clamping arm journaled in a bearing 35 adjustable upon the supporting rod, substantially as described.

4. The main supporting rod, in combination with two clamping arms, having a slideable adjustment thereon, a pivoted clamping arm 40 journaled in a collar and adjustable lengthwise upon said rod, a short transverse shaft also journaled in said collar and provided with an eccentric, a crank arm or lever for operating said shaft, and a link interposed 45 between said eccentric and the pivoted clamping arm, all arranged for joint operation, substantially as described.

5. The main supporting rod, in combination with a series of clamping arms adjustable 50 lengthwise upon said supporting rod, and a series of clamping bars adjustable upon said

clamping arms, whereby the device may be adjusted to articles of different sizes, substantially as herein described.

6. The combination of the main supporting 55 rod, the adjustable clamping arms and the clamping bars adjustable thereon, the supporting hook, and the swiveled block or yoke, substantially as and for the purpose specified.

7. The main supporting rod, the adjustable 60 clamping arms thereon and the clamping bars adjustable upon said clamping arms, in combination with the supporting hook swiveled upon said rod, means for adjusting the position of said hook, and an adjustable weight 65 mounted on said supporting rod for counterbalancing the weight of the articles carried by the clamping arms and bars, all arranged in the manner substantially as described.

8. The main supporting rod, the adjustable 70 clamping arms thereon, and the clamping bars adjustable on said clamping arms, in combination with the supporting hook swiveled on said rod, means for adjusting the position of said hook, the adjustable weight mounted on 75 said supporting rod for counterbalancing the weight of the articles carried by the clamping arms and bars, and a handle connected with said supporting rod, whereby the tongs may be elevated and lowered and otherwise handled and controlled by the operator, in the manner specified.

9. The main supporting rod, the adjustable clamping arms thereon, and the clamping bars adjustable on said clamping arms, in combination with a sliding adjustable collar mounted on said rod, a clamp pivoted thereto, a rock shaft also mounted in said adjustable collar, and provided with an eccentric, a link interposed between said eccentric and the pivoted 90 clamping arm, a crank arm or lever for operating said shaft, and a stop for limiting the throw of said crank arm or lever, substantially as and for the purpose specified.

In testimony that I claim the foregoing as 95 my own I have hereto affixed my signature in the presence of two witnesses.

AIMÉ LOUIS VUILLIER.
